United States Patent

Des. 242,178
Patented Nov. 2, 1976

242,178

SPHYGMOMANOMETER

Mario Saenz-Arroyo, Mexico City, Mexico, assignor to
Articulos Medicos Mexicanos, S.A.

Filed Feb. 9, 1976, Ser. No. 656,678

Term of patent 14 years

Int. Cl. D24—02

U.S. Cl. D83—12 R

Fig. 3.

Fig. 4.

FIG. 1 is a front elevational view of a sphygmomanometer, showing my new design;

FIG. 2 is a side elevational view of the sphygmomanometer;

FIG. 3 is a rear elevational view of the sphygmomanometer; and

FIG. 4 is a plan top view of the sphygmomanometer.

I claim:

The ornamental design for a sphygmomanometer, as shown.
